UNITED STATES PATENT OFFICE

GEORGE A. KEEBS, OF MEMPHIS, TENNESSEE, ASSIGNOR, BY MESNE ASSIGNMENTS, TO
PLOUGH, INC., OF MEMPHIS, TENNESSEE, A CORPORATION OF DELAWARE

ARTICLE DISPLAYING AND VENDING CABINET

Application filed April 3, 1929. Serial No. 352,239.

My invention relates to an article displaying and vending cabinet, and it is an object of the invention to provide a device of this character, in which articles such as for example aspirin or the like contained in small boxes may be shipped, displayed and vended; all as will be hereinafter more particularly described and claimed.

Referring to the accompanying drawings, which are made a part hereof, and on which similar reference characters indicate similar parts,

Figure 1 is a rear perspective illustrating one application of my invention,

Figure 2, a plan view of the blank which forms the compartments of the carton,

Figure 3, a rear elevation with the supporting member flat or in the position for packing and shipping,

Figure 4, a transverse section on line 4—4 of Fig. 3,

Figure 5, a longitudinal section on line 5—5 of Fig. 3, and

Figure 6 is a perspective of the device.

In the drawings, reference character 10 indicates the front of an article displaying and vending cabinet having a plurality of upright slots or openings 11 behind which the articles displayed are adapted to be stacked. Enlarged openings 12 at the bottom of each slot serve to permit the removal of the lowermost article in the stack. Also if desired, the device may be refilled by insertion through these enlarged openings. The front member 10 is of a flat piece of relatively stiff material, such as for example cardboard or the like, behind which are secured compartment forming members 13 and 14.

The member 13 is of the form shown in Fig. 2, and is provided with transverse crease lines 15 and 16 and longitudinal crease lines 17 and 18, the blank being folded along the lines 15 to form the sides 19 of each compartment, and being folded along the lines 17 to form the ends 20 of each compartment. The blank is also folded along the crease lines 16 and 18 to provide flat portions 21 and 22 parallel to the main body of the blank, held in spaced relation to the blank by the just described side portions. The blank when

thus folded will therefore provide rectangular compartments having bottoms 23 open at their tops which are disposed directly behind the slots in the front member 10 when the blank 13 is folded and secured in position on the rear face of the front member. It will be noted that the portions 22 and 23 are arranged in alternate or staggered relation and that the width of the portions 22 are much less than the width of the portions 23 in order to space the compartments fairly close together. The member 13 is fastened to the back of the member 10 by cement and also by staples 24, twelve staples being used, three along each edge of the device.

A re-enforcing back 25 is secured over the member 13 and has its ends turned down at 26 at right angles to the body 25 and paralleling the portions 20 of the blank 13, and its extremity 27 is then turned outwardly in parallel relation to its body 25, flat against the portion 21 of the blank 13. The member 25 is purely a re-enforcing member which is secured in position by cement and by the staples 24.

In order to support the cabinet in slightly inclined position best adapted for advantageously displaying the same and the contents thereof, I provide an easel formed of a blank 28 of a single piece of relatively stiff cardboard or the like, provided with substantially parallel longitudinal crease lines 29 defining a central longitudinal attaching section 30 and side wings or supports 31 which preferably are tapered from bottom to top, and which are tapered along their bottom edges 32 corresponding to the angle at which the device is desired to be supported. The wings are adapted to be locked in extended position at right angles to the attaching section 30 by means of a flap 33 formed integrally with the easel blank by cutting the blank, beginning at the edge of the attaching section outwardly along the line 34 and across the side 35, which forms the free edge of the locking flap 33 with crease lines 36 being provided in order to cause the flap to fold downwardly to a position at right angles to the attaching section of the body of the blank, and in order to secure the wings 31

firmy in fixed position notches 37 and 38 are formed in the flap, the notches 37 riding past the protuberances 39 on the wing formed by the notches 38 as shown in Fig. 1. The wings 5 are flat against the back of the box when the box is not in display position, being readily moved outwardly to support the box upon a counter or the like from which the goods are adapted to be removed. In order to facilitate the removal of the articles from the cabinet, a plurality of openings 40 are provided, one through the rear of each compartment, 10 through which the finger may be inserted for slightly elevating and pushing out the article contained in the lower end of the compartment.

While I have described my device as intended primarily for the display of metal boxes of aspirin, I do not limit myself to such use, but the same is merely for the purpose 20 of illustration.

It will be obvious to those skilled in the art that various changes may be made in my device without departing from the spirit of 25 the invention, and I, therefore, do not limit myself to what is shown in the drawings and described in the specification, but only as set forth in the appended claims.

Having thus fully described my said invention, what I claim as new and desire to 30 secure by Letters Patent, is:

1. A display cabinet or carton comprising a relatively stiff front member, a compartment forming member secured to the rear 35 face of the front member and including a body having a plurality of transverse folds disposed longitudinally of the front member defining rectangular compartments disposed in slightly spaced parallel relation and of a depth to house articles therein, the ends of 40 said compartments being closed by portions formed integrally with the compartment forming blank and secured to the front member of the cabinet, and means for supporting 45 the cabinet in a position for displaying articles contained therein, substantially as set forth.

2. A display cabinet or carton comprising a relatively stiff front member, a compartment forming member secured to the rear 50 face of the front member and including a body having a plurality of transverse folds disposed longitudinally of the front member defining rectangular compartments disposed 55 in slightly spaced parallel relation and of a depth to house articles therein, the ends of said compartments being closed by portions formed integrally with the compartment forming blank and secured to the front member 60 of the cabinet, and means for supporting the cabinet in a position for displaying articles contained therein, and a re-enforcing member secured on the back of the device and having its ends bent down into snug engagement 65 with the extremities of the exterior

surfaces of the compartments and secured to the front member, substantially as set forth.

3. A display cabinet comprising a front member adapted to be supported substantially in upright position, a compartment forming member secured transversely of the front member and provided with creases defining upright elongated compartments, and a reinforcing member secured longitudinally of the front member over the rear side of the compartment forming member, substantially as set forth.

In witness whereof, I have hereunto set my hand at Memphis, Tennessee this 29th day of March, A. D. nineteen hundred and 80 twenty-nine.

GEORGE A. KREBS.
